UNITED STATES PATENT OFFICE.

EDWIN B. GILLINDER, OF PORT JERVIS, NEW YORK, ASSIGNOR TO GILLINDER BROTHERS, INC., OF PORT JERVIS, NEW YORK, A CORPORATION OF NEW YORK.

DESIGN FOR A LIGHT-DIFFUSING FIXTURE.

Application filed April 21, 1928. Serial No. 26,406. Term of patent 7 years.

To all whom it may concern:

Be it known that I, EDWIN B. GILLINDER, a citizen of the United States, and a resident of Port Jervis, county of Orange, and State of New York, have invented a new, original, and ornamental Design for a Light-Diffusing Fixture, of which the following is a specification, reference being had to the accompanying drawings, forming part thereof, of which—

Fig. 1 is a side view of a light diffusing fixture embodying my invention.

Fig. 2 is a bottom view of the light diffusing fixture, showing the opaque ornamental annular member at the outer portion of the diffusing globe.

I claim:

The ornamental design for a light diffusing fixture, as shown.

EDWIN B. GILLINDER.
